CLAIM

The ornamental design for a nail polish cabinet, as shown and described.

DESCRIPTION

FIG. 1 is a front perspective view of the nail polish cabinet showing my new design;

FIG. 2 is another front perspective view showing the drawer tray opened;

FIG. 3 is a front elevation view thereof;

FIG. 4 is a left elevation side view thereof; and,

FIG. 5 is a top plan view thereof.

The broken lines disclose portions of the nail polish case which form no part of the claimed design.
